Primary Examiner — Rashida Johnson*(74) Attorney, Agent, or Firm* — Dority and Manning, PA**CLAIM**

The ornamental design for coveralls with angled stretch panel, as shown and described.

DESCRIPTION

FIG. 1 is a front view of apparel laid flat with an angled stretch panel according to the present design; and, FIG. 2 is a rear view of the apparel illustrated in FIG. 1 laid flat showing the angled stretch panel according to the present design.

In FIGS. 1 and 2, the broken lines represent portions of the design which form no part of the claim.
